UNITED STATES PATENT OFFICE.

JOHN W. ADAMS. OF SAVANNAH, GEORGIA.

STREET INDICATOR.

Application filed October 9, 1922. Serial No. 593,311.

To all whom it may concern:

Be it known that I, JOHN W. ADAMS, a citizen of the United States, residing at Savannah, in the county of Chatham and 5 State of Georgia, have invented new and useful Improvements in Street Indicators, of which the following is a specification.

This invention relates to street indicators especially adapted for use in connection 10 with electric cars.

The primary object of the invention is to provide a device of this character which will indicate to the passengers in the car the next approaching street in time to permit them to 15 give the proper signal to stop the car when they have reached their destination.

Another object is to provide an electrically controlled device which will be automatically operated in advance of the street 20 indicated, and will notify passengers of the change of street indication by means of an audible or other signal.

A further object is the production of a street indicator which is positive in operation 25 and capable of being used at either end of the car, or reversed to permit use thereof under various conditions.

With the above objects in view the invention 30 consists of the following novel combination and arrangement of parts, herein-after more fully described, illustrated in the accompanying drawings and pointed out in the claims hereto appended.

In the drawings;

Figure 1 is a view in diagram of a portion 35 of an electrically operated car having the invention applied thereto, the trolley wire and the suspending wires being also shown;

Figure 2 is a vertical sectional view through the indicating mechanism;

Figure 3 is a detailed sectional view on the line 3—3 of Figure 2;

Figure 4 is a detailed sectional view 45 through the retarding cylinder and showing the valve for regulating the speed of the return movement of the piston;

Figure 5 is an enlarged detail view of the 50 depending spring hinge contacts and the provision of the trolley wire and the suspending wires; and

Figure 6 is a detailed elevation of the end- 55 less chains and the street indicating panels carried thereby;

Figure 7 is a fragmentary sectional view

illustrating the manner of mounting the shiftable reversing gears.

In its practical form the invention includes a casing A in which is housed the indicating mechanism, the said casing being 60 adapted to be secured at either end of an electric car B as illustrated diagrammatically in Figure 1. The invention also includes the movable or travelling contact C, which is carried by the trolley pole D 65 and is located in the path of the depending spring contacts E, which are secured to the suspending wires F, which carry the trolley wire G.

Located within the casing A is an insulated metal supporting frame 10, with brackets 11, having bearings for the shaft 12. Also included in the frame 10 is a bracket 13, a shaft 14 having bearings therein, and upon this shaft is mounted a pair of 70 sprocket wheels 15. A shaft 16, which is mounted in bearings provided within the casing, has secured thereon a pair of sprocket wheels 17, and these sprocket 75 wheels and the sprocket wheel 15 are connected together by means of chains 18. These chains are operated by a means later explained and are connected by means of panels 19 upon which is printed or otherwise indicated the names of various streets passed 80 by the car. The front of the casing A is provided with a magnifying lens 20 for the purpose of viewing and enlarging the names upon the panels 19. The invention provides means by which the position of the lens may 85 be changed, and for this purpose the said lens is secured to a curtain 21 which covers the upper portion of the front of the casing and is mounted upon rollers 22 and 23, the said curtain being secured in adjusted position by means of the set screw 24.

For the purpose of driving the chains 18, the shaft 14 is provided with a gear 25, which meshes with an idler gear 26, the gear 26 engaging a gear 27 secured to the driving shaft 12. In order to reverse the direction of travel of the sprocket chains 18, the gear 27 also engages a gear 28, which meshes with an idler 29 which is adapted to be brought into engagement with the gear 25. 105 When the gear 29 is engaged with the gear 25, the gear 26 is disengaged therefrom in order to permit the reverse movement of the chains 18. For the purpose of shifting the gear 26 and 29, the said gears are mounted 110

upon a pivoted bar 30 in a manner to permit of the engagement of the gear 26 with the gear 25, and the disengagement of the gear 29 and vice versa as desired. For this purpose the pivot of the bar 30 is carried by an internally threaded socket bearing 30^a, which operates in a slot provided in the casing A and which is held in adjusted position by means of a handle 30^b. This handle has a threaded engagement with the bearing 30^a. The gearing just described is driven by a ratchet mechanism which is electrically operated. This mechanism includes the ratchet 31 which is secured to the shaft 12 and is driven by means of the loosely pivoted operating dog 32 which is carried by the pivoted operating bar 33. The frame 10 supports a spring 34, by means of which the dog 32 is urged into engagement with the teeth of the ratchet wheel 31. Upon the opposite side of the wheel 31 there is provided a spring locking pawl 36 for the purpose of preventing a retrograde movement of the sprocket wheel. The bar 33 is pivoted upon the frame as indicated at 37 and the short arm of this bar carries an armature 38, which is controlled by an electromagnet 39. The magnet 39 is included in an electric circuit, one wire 40 of which connects to one of the depending spring contacts E. The other wire 41 has included therein a switch, the contacts of the said switch being secured to the inside of the casing A as shown at 42 and 43. The end of the wire which connects the contact 32 is grounded in any convenient manner. In order to normally close the switch just described, the bar 33 is provided upon the end opposite the armature 38 with a movable contact element 44 so that when the parts are in their normal or initial position the switch just described is closed. Secured to the bar 33 is a spring 45, which acts to bear down this end of the bar and keep the contacts 42, 43 and 44 in engagement. The spring 45 is provided with tensioning means in the form of a thumb nut 46. In order to prevent a too rapid return of the bar 33 after it has been operated by the magnet 39 and the circuit broken, there is provided a retarding air cylinder 47. Pivoted to the bar 33 is a rod 48, and the opposite end of this rod is provided with a piston 49 which operates within the cylinder 47. By this construction the return of the bar 33 under the action of the spring 44 will be retarded, and the speed of its return may be controlled by means of a regulating valve 50 located within the lower end of the cylinder 47. Also included in the circuit wire 40 is an

audible signal 51 in the form of a bell, which is adapted to be operated upon the closing of the circuit and the operation of the indicating mechanism.

The depending contacts E are located a suitable distance in advance of the street crossings in order to permit the occupants of the car sufficient time to give the proper signal to stop the car and one of these contacts E is provided for each crossing. As the movable contact C engages the contact E the magnet 39 is energized and attracts the armature 38 to cause the swinging of the bar 33 upon the pivot 37. The upward movement of one end of the bar will cause the dog 32 to engage a tooth of the ratchet 31 and rotate the shaft 12 a sufficient distance to operate the gearing to move the chains 18 and expose the panel of the next succeeding street. The upward movement of the bar 33 will cause the breaking of the circuit through the contacts 42, 43 and 44 and owing to the retarding action of the cylinder 47 the contacts C and E will become disengaged before the return of the bar 33 to its initial position.

The hand operated switch 51 is included in the circuit, connected with a convenient source of supply for the purpose of operating the mechanism to reverse the street indication when desired.

From the foregoing description it is believed that the construction, operation and advantages of the invention will be fully understood and a further explanation is therefore unnecessary.

Having described the invention what I claim, is:

A street indicator for vehicles comprising an endless belt and gearing for operating the belt, a pivotally mounted switch lever, a contact element carried by one end of the lever, spaced contacts located in the path of and normally bridged by the lever carried contact, an electromagnet included in circuit with the spaced contacts and with a source of current, means whereby a circuit may be completed through the magnet to energize the latter, an armature carried by the opposite end of the switch arm within the field of the magnet, whereby the arm may be actuated to interrupt the circuit, means connected to the switch arm and engaging the gearing for actuating the latter to operate the belt when the switch arm is operated, means for returning the switch arm to normal position and means for retarding the return movement of said arm.

In testimony whereof I affix my signature.
JOHN W. ADAMS.
